Electric Industrial Co., Ltd., Osaka, Japan, a corpora-
tion of Japan

Filed Oct. 3, 1968, Ser. No. 13,827

Claims priority, application Japan Apr. 12, 1968

Term of patent 14 years

Int. Cl. D14—03, 04
U.S. Cl. D26—14

FIG. 1

FIG. 2

FIG. 3

FIG. 1 is a front elevational view of an amplifier showing our new design;

FIG. 2 is a left side view therof; and

FIG. 3 is a top and front perspective view thereof, showing a switchboard cover in open position.

The bottom and rear surfaces of the amplifier are flat and unornamented.

We claim:

The ornamental design for an amplifier, as shown and described.
